UNITED STATES PATENT OFFICE.

HUGH CHRISTIE, OF BOSTON, ASSIGNOR TO THE BIGELOW CARPET COMPANY,
OF CLINTON, MASSACHUSETTS.

DESIGN FOR A CARPET.

SPECIFICATION forming part of Design No. 12,434, dated August 30, 1881.

Application filed August 6, 1881. Term of patent 3½ years.

To all whom it may concern:

Be it known that I, HUGH CHRISTIE, of Boston, in the county of Suffolk and State of Massachusetts, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet bearing my new design.

The group A is composed of a square, 8, and 15 of a parallelogram, 7, which are joined by a bouquet, 6. Said bouquet has upwardly-projecting sprays, 9, and downwardly-projecting sprays, P. The square 8 has also a projecting triangle formed on one of its sides, and its 20 groundwork is dotted, as indicated. The groundwork of the parallelogram 7 is dotted with small crosses, and contains a triangle that projects into it.

The group B, which is connected to the 25 group A by one of the sprays 9, contains a checkered parallelogram, 4, placed against a rectangle, 3, which, by a bouquet, 1, connects with a circular figure, 2, that has zigzag lines on its background. A spray, 5, extends from 30 the circular figure into contact with the square 8 of the figure A, as shown, on the right side of the photograph. Another spray, M, extends from the bouquet 1 downwardly between the figures 2 and 3, as shown.

35 The group C, which is above the square 8 and the spray 5, consists of a large square with dotted background, (marked v,) said square being partly covered and concealed by a bouquet, w, from which extend sprays x, z, and y. 40 The end of the spray y is shown above the group B on the left side of the photograph, and reaches close to a spray, s, of the group D. This group D, which is directly above the group A, consists of the rectangular figure t and spider-web-like figure u, both said figures being partly concealed by a large bouquet, q, having upwardly-projecting sprays, r, and 45 downwardly and sidewardly projecting sprays, s. One of the sprays r—to wit, the one extending to the left—reaches contact with the octagonal figure o of the group E. This group

50 E, of which part is shown at the right side and the other part at the left, of the photograph,

consists of the octagon o and of a parallelogram, p, both of which are covered by the bouquet m, having projecting sprays n. One of the sprays n reaches close to the group F, which is directly above the group D, and is composed of a parallelogram, k, a rectangle, h, and of a square figure, f, having its corners 55 cut out. These three geometrical figures are partly covered by a bouquet, g, having sprays i, j, and l, as shown. The spray l reaches nearly to and serves to connect the group H with the group F. This group H is very similar to the group C, differing from it principally in the style of groundwork for its square figure c, which in group H is made of continuous bent lines and in group C dotted. In other words, the group H consists of a large square, 60 c, partly concealed by bouquet a, having sprays b, d, and e. The spray e reaches nearly to a projecting spray of the group G, which group G is very much like the group D, having also rectangle marked T and the spider-web-like 65 lower figure. The difference between the groups D and G is simply in the groundwork for the rectangle, which, in group D, is composed of alternate dark and light checkers, and in group G of obliquely-placed parallel zigzag 70 lines.

I claim—

1. The design for carpets, consisting of the group A, composed of figures 6, 7, 8, 9, and P, substantially as shown. 85
2. The design for carpets, consisting of the group B, composed of figures 1, 2, 3, 4, 5, and M, substantially as shown. 90
3. The design for carpets, consisting of the group C, composed of figures v, w, x, y, and z, substantially as shown. 95
4. The design for carpets, consisting of the group D, composed of figures q, r, s, t, and u, substantially as shown. 100
5. The design for carpets, consisting of the group E, composed of figures m, n, o, and p, substantially as shown.
6. The design for carpets, consisting of the group F, composed of figures f, g, h, i, j, k, and l, substantially as shown.
7. The design for carpets, composed of the groups A, B, C, D, E, F, G, and H, substantially as shown.

Witnesses: HUGH CHRISTIE.
